(57) **CLAIM**

The ornamental design for a stand monitor, as shown and described.

DESCRIPTION

FIG. 1 is a perspective view of a stand monitor showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the stand monitor where the stand monitor is in a first configuration of use;

FIG. 10 is a perspective view of the stand monitor where the stand monitor is in a second configuration of use; and,

FIG. 11 is an enlarged view of portion 11 shown in FIG. 2. The broken lines in the drawings depict portions of the stand monitor that form no part of the claimed design. The dash-dot lines in FIGS. 2 and 11 identify the location of the enlarged view and form no part thereof.
